UNITED STATES PATENT OFFICE.

JOHN J. GROSS, OF TOLEDO, OHIO.

GAGE FOR GASOLENE-TANKS.

1,242,176.

Specification of Letters Patent.

Patented Oct. 9, 1917.

Application filed May 19, 1916. Serial No. 98,662.

To all whom it may concern:

Be it known that I, JOHN J. GROSS, a citizen of the United States, residing at Toledo, in the county of Lucas, State of Ohio, have 5 invented certain new and useful Improvements in Gages for Gasolene-Tanks; and I do hereby declare the following to be a full, clear, and exact description of the invention, such as will enable others skilled in the art 10 to which it appertains to make and use the same.

This invention relates to improvements in gages and has special reference to gages for gasoline tanks, used on automobiles and 15 other like vehicles.

The principal object of the invention is to provide an improved and simplified form of device of this character wherein the height of the gasoline can readily be ob- 20 served from either side of the automobile.

Another important object of the invention is to provide a novel means for holding the gage glass or tube in such manner that the vibrations due to the running of the 25 automobile will not cause fracture of such glass.

A still further object of the invention is to provide a novel and improved form of end member for gages of this description 30 wherein provision will be made for firmly holding or grasping the gage glass so that the latter will not vibrate.

With the above and other objects in view, as will be hereinafter apparent the invention 35 consists in general of certain novel details of construction and combinations of parts hereinafter fully described, illustrated in the accompanying drawing, and specifically claimed.

40 In the drawing, like characters of reference indicate like parts in the several views, and:

Figure 1 is a side elevation of the device as applied to the dash of an automobile;

45 Fig. 2 is a vertical section of the device as applied to the seat panel of an automobile;

Fig. 3 is a front elevation of the gage;

Fig. 4 is a plan view thereof as applied 50 to the seat panel;

Fig. 5 is an enlarged detail section on the line 5—5 of Fig. 3;

Fig. 6 is a detail section on the line 6—6 of Fig. 2.

55 The form of the device as applied either to the seat panel or the dash of an auto-

mobile is substantially the same, the only difference being that in the latter case a suitable vent is provided in connection with such device, all of the main parts remaining 60 the same.

In the embodiment of the invention herein illustrated there is provided a base member 10 which has suitable openings for the reception of screws 11 used to secure the 65 base member to the panel or dash or such other support as may be desired.

This base member extends vertically and at each end thereof there is fixed to the base member, as by the rivets 12 an end member 70 or casting which forms a fitting for the connection of a gage glass with the pipes connecting the device with the tank. The upper end member is indicated in general at 13, while the lower end member is similarly indicated at 14.

This upper end member is preferably in the form of a die casting and consists of a body 15 having a bore 16 extending vertically therethrough. The lower part of this 80 bore is smooth as at 17 and opens downwardly. Communicating with this bore between the smooth portion and the upper end thereof is a lateral passage or opening 18 which has its outer end arranged to 85 receive a pipe or tube as at 19. Between the smooth portion of the bore and the opening 18 the bore is threaded in a suitable manner to receive the threaded sleeve 20, the under side of which thus forms an adjustable shoulder for purposes hereinafter 90 to be described. Between the opening 20 and the upper end of the bore the latter is threaded to receive a pipe plug 21. This pipe threaded portion is, of course, slightly 95 larger than the threaded portion below the opening so that ready introduction of the sleeve 20 is permitted. Moreover, the sleeve 20 is provided with some suitable means, such as lugs 22 for the engagement of a 100 screw driver or wrench so that the sleeve may be adjusted vertically in the lower threaded portion of the fitting.

The fitting 14 is similar to the fitting 13 being provided with a body portion 23 having a bore 24 which extends downward from the top of the fitting and terminates in a reduced shoulder portion 25. This shouldered portion has leading laterally therefrom a passage or opening 26 provided with means 110 at its end to connect a pipe, as indicated at 27.

Each of the end fittings is provided with a wedge shaped seat 28 terminating in an abrupt shoulder 29. At 30 is indicated a scale, V-shaped in cross section and having its ends secured in the seats 28 and it is to be noted that the apex of the V is directly in front of the axis of the bores 16 and 24. On each leg of the V there is inscribed a suitable scale as indicated clearly in Fig. 3 10 so that the scale can be read either from in front or from either side of the gage.

At 31 is indicated a gage glass, the lower end whereof rests on a suitable elastic collar or gromet 32 which in turn rests on the 15 shoulder at the bottom of the main portion of the bore 24. The upper end of this tube or glass 31 extends into the smooth portion of the bore 16 and on top of this upper end is positioned a washer or gromet 33 of 20 similar material to the gromet 32. The sleeve 20 bears upon this gromet 33 and by screwing this sleeve downward the glass 31 may be tightly held between the two gromets.

Each of the end fittings is connected by 25 a pipe 34 to a union 35 which is in turn connected by suitable pipes and bends indicated at 36, to the tank 37, care being taken to have the bottom of the tank in alignment with the zero of the gage 30. A 30 valve 38 may be applied in connection with the lower pipe 36 so that the flow of liquid from the tank 37 will be cut off when the valve is closed.

In the form wherein the device is applied 35 to the dash of an automobile the upper pipe 34 is omitted, and in place of this pipe 34 there is provided a pipe 39 which communicates with a suitable vent 40 so that but one pipe is needed to connect the gage 40 to the gasolene tank.

It is preferable to divide the scale so that 45 gallons and parts of gallons will be indicated thereon but any other suitable division may be employed, which may be found convenient.

It will also be obvious that the device may be used with other liquids than gasolene but when so used or when used with any liquid in which there is practically no color a suit-

able colored float 41 is preferably placed in 50 the gage glass so that the position thereof may indicate the top of the liquid column in such glass.

In assembling the device, it is necessary to remove the plug 21 and sleeve 20. The 55 lower gromet 33 may then be placed in the lower fitting. The tube 31 is then slid down through the upper bore 16 and the upper gromet placed thereon. The sleeve 20 is then screwed into position to bear firmly 60 against the upper gromet whereupon the operation is completed by inserting the plug 21.

There has thus been provided a simple and efficient device of the kind described 65 and for the purpose specified.

It is obvious that many minor changes may be made in the form and construction of the invention without departing from the material principles thereof. It is not 70 therefore desired to confine the invention to the exact form herein shown and described but it is wished to include all such as properly come within the scope claimed.

What is claimed is:

A device of the character described comprising in combination with a receptacle, pipes communicating with the receptacle at diametrically opposite points, a casting provided with eight angular communicating 80 passages and carried by the receptacle in alignment with one of said pipes, a second casting provided with a right angular passage and secured to said receptacle in alignment with the other of said pipes and having one end of its right angular passage in alignment with one end of the right angular passage in the first mentioned casting, a transparent tube having its ends secured in said castings, and an indicating scale carried by the castings and supported thereby in juxtaposition to said transparent tube.

In testimony whereof, I affix my signature, in the presence of two witnesses.

JOHN J. GROSS.
